UNITED STATES PATENT OFFICE.

STEPHEN C. MENDENHALL, OF RICHMOND, INDIANA.

CASTER.

SPECIFICATION forming part of Letters Patent No. 314,952, dated March 31, 1885.

Application filed September 3, 1884. (No model.)

To all whom it may concern:

Be it known that I, STEPHEN C. MENDENHALL, a citizen of the United States, residing at Richmond, in the county of Wayne and State of Indiana, (present business address Cincinnati, Ohio,) have invented certain new and useful Improvements in Casters for Furniture and other Articles, of which the following is a specification.

It has been before proposed to employ anti-friction rollers placed within a circular rim cast on the socket or pod of a stem-caster. The difficulty here was, that the stem being cast solid was subsequently bored out for the socket, necessarily involving large expense. To avoid this evil I cast the pod in two equivalent parts, each bearing one half of the flange and rim at bottom and fixed together when in use by a rivet or screw at top.

I am aware that sockets for stem-casters have before been cast in two parts, but believe that it has never before been proposed to cast a socket having a rim for retaining the anti-friction rollers in two parts. The two-part pod or socket is held together at bottom by a band or ring surrounding the rim of the pod, and having a flange at bottom projecting in around the spindle to hold the anti-friction rollers in place. When the two parts of the pod are placed together, the loose rollers dropped into their annular chamber, and the outside ring pressed forcibly on, the top is complete and is ready to be driven into its socket in the furniture-leg.

It may sometimes be necessary to employ, in addition to the outer band, a smooth metal ring placed within the rim of the pod, to afford a perfectly even bearing for the rollers, notwithstanding any asperities or imperfect joints in the rim.

In order that my invention may be more fully understood, I will proceed to describe it with reference to the accompanying drawings, in which—

Figure 1 is a perspective view of a caster embodying my invention. Fig. 2 is a vertical sectional view of the same. Fig. 3 is a similar view taken in a plane at right angles to that of Fig. 2, and showing in addition the inner bearing-ring. Fig. 4 is an elevation of

a half-pod detached. Fig. 5 is a plan of the band. Fig. 6 is an under side view of the pod shown in Fig. 3, showing the anti-friction rollers in place.

The pod, socket, or stem of my improved 55 caster is cast in halves, 1 2, with half-flanges 3, having downwardly-projecting rims 4. An annular flange, 7, may be formed on the band 6 by stamping; or it may be made separate and attached thereto or to the pod in 60 a suitable manner. Its office is to form in connection with the flange 3 and rim 4 a closed chamber, within which the loose anti-friction rollers 8 are retained. The rollers 8 are made of such a size and number that but a small 65 space, 9, is left between the end rollers of the series when placed in the chamber, as shown in Fig. 6. Freedom of motion is thus allowed, while the rollers are prevented absolutely from falling out unless the pod be taken to 70 pieces. This matter is, however, to be made the subject of a separate application for Letters Patent.

As there may be slight irregularities due to faulty castings and imperfection of joint 75 between the two parts of the rim 4, I employ a ring, 10, of smooth metal, which is dropped into the pod, it being of such diameter as to fit closely within the rim 4.

The two parts 1 2 of the pod, being cast horizontally, may be provided with cast ribs 11, which enter the wood when the top is driven into place, and so retain it in the furniture-leg. The spindle 12 is cast with a groove, as shown at 13, the shoulder 14 thus formed at 80 the top of spindle serving, in connection with the pin 15, to retain the spindle in its place in non-separating casters. By thus forming the spindle a large gain in the amount of metal employed is effected. 85

Having thus described my invention, what I claim as new, and desire to secure by Letters Patent, is—

1. In combination with a two-part stem-caster socket-top, a band or rim pressed closely around the bottom thereof for holding the two parts together, substantially as set forth. 95
2. In combination with a two-part stem-caster socket-top having bottom flange and rim projecting downward therefrom, the band 100

or rim surrounding said rim and pressed closely thereon, loose anti-friction rollers, and a retaining flange or disk below said rollers, forming with the socket-flange and rim a closed chamber, substantially as set forth.

3. In combination with a two-part stem-caster socket-top riveted together at top and fastened by band or ring at bottom, the loose anti-friction rolls or rollers, as set forth.

4. In combination with a caster socket-top

having an annular enlargement or chamber at bottom, loose horizontal rolls occupying said chamber and a smooth ring or way for said rolls within said chamber, substantially as set forth.

STEPHEN C. MENDENHALL.
